(57) **CLAIM**

We claim the ornamental design for a charging connector with lock, as shown and described.

DESCRIPTION

FIG. 1 is a perspective view of a charging connector with lock.

FIG. 2 is a front view of the charging connector with lock of FIG. 1.

FIG. 3 is a rear view of the charging connector with lock of FIG. 1.

FIG. 4 is a right side of the charging connector with lock of FIG. 1.

FIG. 5 is a left side view of the charging connector with lock of FIG. 1.

FIG. 6 is a top view of the charging connector with lock of FIG. 1.

FIG. 7 is a bottom view of the charging connector with lock of FIG. 1.

FIG. 8 is a perspective view of another charging connector with lock.

FIG. 9 is a front view of the charging connector with lock of FIG. 8.

FIG. 10 is a rear view of the charging connector with lock of FIG. 8.

FIG. 11 is a right side of the charging connector with lock of FIG. 8.

FIG. 12 is a left side view of the charging connector with lock of FIG. 8.

FIG. 13 is a top view of the charging connector with lock of FIG. 8; and,

FIG. 14 is a bottom view of the charging connector with lock of FIG. 8.

The broken lines shown represent portions of the charging connector with lock that form no part of the claimed design. Where dash-dot-dash broken lines abut the shaded surface it is understood that those broken lines represent unclaimed

(Continued)

boundary between claimed and unclaimed surfaces. None of the broken lines form any part of the claimed design.
